UNITED STATES PATENT OFFICE.

MAURICE H. MANDELBAUM, OF CHICAGO, AND BESTER R. WEBSTER, OF ELGIN, ILLINOIS, ASSIGNORS, BY DIRECT AND MESNE ASSIGNMENTS, TO BRANDT CASHIER COMPANY, A CORPORATION OF ILLINOIS.

COIN-LOCKING MECHANISM.

1,376,959.

Specification of Letters Patent.

Patented May 3, 1921.

Application filed January 19, 1920. Serial No. 352,285.

To all whom it may concern:

Be it known that we, MAURICE H. MANDELBAUM and BESTER R. WEBSTER, citizens of the United States; and residents of Chicago, in the county of Cook, State of Illinois, and Elgin, in the county of Kane, State of Illinois, have invented certain new and useful Improvements in Coin-Locking Mechanism, of which the following is a specification.

Our invention relates to change making machines and particularly to a novel coin ejector-lock adapted for use in connection with devices of the type described.

Our invention may be considered as an improvement on the device illustrated in Reissue Patent No. 14,227, of December 12, 1916, to E. J. Brandt. One of the principal objects of the construction here illustrated is to provide an extremely simple mechanism which is gravity actuated and therefore requires no springs. A further object is to provide a device so arranged as not to interfere with the position or operation of the coin ejector and which will operate notwithstanding the presence of worn, mutilated or imperfect coins.

In machines of the type described a supply of coins is maintained in suitable chutes provided in a tray. The chutes must be of such diameter as to provide freedom of movement between the coins and all possible points of contact of the coins with the sides of the chute in order to allow for variation in the diameter of different coins of the same denomination and the further variations caused by wear. It is furthermore desirable to provide for a maximum of freedom of movement between the coins and the side walls in order to facilitate the filling of the chute. Where a detector is adapted to cooperate with coins in the stack it will be seen that its operation is uncertain if the coin or coins with which it engages do not always occupy the same relative position and this difficulty is experienced where a detector having a single finger is employed. However, by employing a detector comprising two fingers which engage the coin at separated points the possibility of improper operation, due to movement of the coins in the chute, is eliminated.

By the use of a detector having two fin-

gers we secure a further advantage. Where it is desirable to lock only after all the coins except one or two have been discharged the detecting finger must be placed so close to the detector as to necessitate a reduction in the size of these parts and a requirement for greater accuracy in construction and fitting. By providing a detector having two fingers which are mounted for operation in planes on opposite sides of the ejector we are able to offset this difficulty and the detecting fingers may be so positioned as to lock on the last coin if desired.

These and other advantages in the construction about to be described will more fully appear hereinafter.

The invention will be more readily understood by reference to the accompanying drawing wherein;

Figure 1 is a fragmentary vertical sectional view through a change making machine constructed in accordance with our invention;

Fig. 2 is a fragmentary front view thereof;

Fig. 3 is an enlarged sectional view of the bell-crank which constitutes the detector and detent.

Fig. 4 is a fragmentary plan view showing the relation of the detecting fingers to a coin; and,

Fig. 5 is a fragmentary sectional view showing the means for retaining the lock release in a depressed condition.

Referring more particularly to the drawings it will be seen that the device of our invention may be associated with a coin tray or chute 10, a few of the coins 11 being indicated in position in the tray. A coin ejector comprising an ejecting finger 12, actuated by a push bar 13, serves to displace the lowermost of the stack of coins in response to the actuation of the proper key. This mechanism being old it is not specifically illustrated or described herein.

Our invention, which includes means for locking the coin ejector in order to prevent actuation after the stack of coins has become depleted to a predetermined extent, comprises a bell-crank, best shown in Fig. 3, consisting of a metal blank bent to provide a channel-shaped arm 14 constituting a detent, and a pair of arms 15, 15, which constitute detecting fingers. The fingers 15 are

formed as continuations of the sides of the channel-shaped arm 14. The bell-crank is mounted for freedom of movement on a horizontal shaft 16 and, by reason of the construction described, it will be seen that the bell-crank is overweighted at one end whereby the detent arm tends to occupy the position shown in Fig. 1. In this position it is impossible to actuate the coin ejector by reason of the fact that the detent engages with a notch 17, formed in a projection 18 from the ejecting finger 12.

As shown in Fig. 4, we provide the detecting element with two fingers extending through a suitable opening in the wall of the tray and bearing against the sides of the coins retained within the chute. Due to the construction described, the fingers bear against the coins at separated points on the periphery thereof and thus compensate for lateral movement of the coins within the container. This construction provides another advantage. By employing two fingers it will be seen that the detector may be so mounted that the fingers are on opposite sides of the ejecting finger 12, and, therefore, that the device may be adapted to permit operation down to the last coin if desired without interfering with the ejector. This operation is possible in view of the fact that the detector and the ejector occupy different vertical planes. In normal operation it will be seen that the bell-crank is retained with the detent in a raised position, due to engagement of the detecting fingers 15 with a stack of coins, as indicated in dotted lines in the figure.

As a means for disengaging the lock, in order to permit of the discharge of all the coins in the tray, we provide an arm 19 fixed to the shaft 16 and engaged by a rocker 20, pivoted at 21 and adapted to be oscillated by a key 22. The key may be retained in its depressed condition by moving the slide 23, best shown in Fig. 5, a convenient button 24 for that purpose being provided. The shaft 16 carries an arm in the form of a cam 25 mounted beneath the channel-shaped por-

tion of the bell-crank and as the key 22 is depressed this cam is rocked and the detent 50 may be lifted.

It is obvious that the construction described is capable of much modification and such modifications as are within the scope of the claims we consider within the scope 55 of our invention.

We claim:

1. In a coin handling machine having means for holding a stack of coins and coin ejecting means, an automatic lock for said 60 ejector, said lock comprising a pair of separated fingers adapted to bear against the sides of the stack of coins at separated points on the periphery thereof, and a detent controlled by said fingers, said detent being 65 adapted to engage with the ejector when said fingers are allowed to project into the line of the stack of coins, substantially as described.

2. In a coin handling machine having 70 means for holding a stack of coins and coin ejecting means, a gravity acting lock for said ejector, and a pair of detecting fingers adapted to engage at separated points on the periphery of said stack of coins, said 75 fingers serving to control the action of said detent, substantially as described.

3. In a coin handling machine having means for holding a stack of coins and coin ejecting means, the combination of a bell- 80 crank mounted on a horizontal pivot above the coin ejector, one arm of said bell-crank being bifurcated to form two fingers located in vertical planes on opposite sides of said ejector, the other arm of said bell-crank acting as a detent and being adapted to engage the ejector when permitted by the position of the detecting fingers, substantially as 85 described.

Signed at Chicago, Illinois, this 19th day 90 of December, 1919.

MAURICE H. MANDELBAUM.
BESTER R. WEBSTER.
